ALLEN JENNINGS AND HELEN JENNINGS, OF CHAGRIN FALLS, OHIO.

PROCESS OF IMITATING BRICK IN MINIATURE MODELS.

Application filed February 7, 1924. Serial No. 691,320.

To all whom it may concern:

Be it known that we, ALLEN JENNINGS and HELEN JENNINGS, citizens of the United States, residing a Chagrin Falls, county of 5 Cuyahoga, and State of Ohio, have invented a certain new and useful Improvement in Processes of Imitating Brick in Miniature Models, of which the following is a full, clear, and exact description, reference being 10 had to the accompanying drawings.

The practice of those engaged in the building arts, particularly architects and those engaged in the building material business, such as brick and tile manufacturers, is to 15 have models of dwellings and buildings reproduced in miniature which embody and set out the features or products in which they are most interested. For instance, if an architect is having a model built, the general 20 design and outward appearance of the miniature is what he would be the most interested in and in this instance, the manner of reproducing the outward appearance of a dwelling, particularly of a dwelling having stucco 25 or brick walls, in miniature, becomes of major importance when consideration is given to the cost of the model in relation to its utility.

The general object of the present invention, therefore, is the provision of a process 30 for reproducing the outer appearance of brick and tile wall structures, whereby various textures and colors of brick, tile and stucco may be accurately reproduced in miniature models of dwellings and buildings.

Our invention contemplates the use of pigments ground in a suitable vehicle such as oil, which may become partly oxidized or 40 congealed whereby a thick gummy mass may be obtained which may be applied to a supporting medium such as wood, fiber board and the like. In reproducing brick or tile in miniature, the chosen supporting medium 45 is preferably wooden slabs or boards of a thickness corresponding to the thickness of wall in the miniature model. These slabs may be first grooved to produce slots in the surface thereof, spaced apart to correspond to 50 horizontal mortar beds and vertical mortar joints of the brick or tile. The pigment coating may then be applied thereover and subsequently scored or grooved coincident with the underlying grooves or slots in the 55 supporting medium.

A further object of our invention, therefore, is the provision of an apparatus for effecting the formation of grooves or slots in such a supporting medium as above mentioned and which apparatus may also be 60 serviceable in forming continuously extending parallel grooves and intermittent transverse parallel grooves in the applied pigments in spaced relation to correspond to the miniature dimensions of each brick or tile in the wall and thereby reproduce or imitate the horizontal and vertical mortar beds of the brick wall in miniature. 65

Other objects of our invention will hereinafter be set forth in the following description of our process and of the accompanying drawings illustrating a preferred apparatus for carrying out the steps thereof. The essential characteristics of our invention is 70 summarized in the claims. 75

Fig. 1 of the drawings is a plan view of an apparatus for forming parallel grooves in a pigment supporting medium, preferably wood or board; Fig. 2 is a fragmentary cross-sectional view taken substantially along the line 2-2 of Fig. 1; Fig. 3 is a fragmentary cross-sectional elevation taken substantially along the line 3-3 of Fig. 1; Fig. 4 is a perspective view of a rotary tool for use in 80 an apparatus such as is disclosed in Figs. 1 and 3 and which is specifically for the purpose of forming alternate scores in the pigment supporting medium; Fig. 5 is a cross-sectional fragmentary plan view showing 85 the use of the tool illustrated in Fig. 4; Fig. 6 is a corner fragment of a scored pigment supporting slab; Fig. 7 is an enlarged fragmentary perspective view of the slab piece shown in Fig. 6 with the pigment coating 90 applied thereto; Fig. 8 is a detailed cross-sectional view showing the manner of scoring the pigment when once applied to the score slab; Fig. 9 shows an alternate method of forming the scores in the pigment when 95 on the slab; Fig. 10 is a view similar to Fig. 8, showing, however, the use of a tool performing intermittent or broken scores in the pigment, which scores correspond to the vertical mortar joints in each horizontal row 100 of brick; Fig. 11 is a cross-sectional view similar to Fig. 3 showing the use of a plurality of such tools as are illustrated in Fig. 10; Fig. 12 is a perspective view of an alternate form of tool for manually forming the 105 110

intermittent scores in the pigment and slabs; Fig. 13 is a diagrammatic representation of the scores or slots formed in a plastic supporting medium.

5 In carrying out the objects of our invention, we provide a method whereby a miniature reproduction of brick and stucco may be obtained which may be of a color to correspond to the textures of brick or stucco, 10 provision being made to reproduce either rough brick, scored brick, finished brick or glazed brick, and wherein we may use compositions of pigments ground in oil, and which may be mixed plain or used in combination 15 with sand, gravel, clay or powdered marble. The mixture may be worked up to the consistency of a stiff putty whence it may be applied to a supporting medium in the nature of a scored slab, preferably a wooden board $\frac{3}{4}$ " thick, which dimension corresponds to the thickness of a 12" wall on a one inch to the foot scale. Various plastic coatings may be mixed which are applicable to one model. For instance, where the 20 model is a miniature of a proposed dwelling having an exterior finish of stucco with a brick trim or stucco with a stone trim, the combinations would comprise a plastic pigment of a color and texture corresponding to the particular kind of brick chosen for the trim in the building, which may be any type of brick and the stucco would comprise a pigment of corresponding color and general texture to that of cement or stucco 25 finish of the building.

Miniature dwellings or models have been made wherein the walls comprise plaster of Paris having the exterior thereof grooved or scored to form scores corresponding to the 30 horizontal and vertical mortar joints of courses of brick. A particular advantage in our method, however, is that we obtain the advantage of a scored pigment supporting medium which we prefer to form of wood 35 with apparatus such as is disclosed in the drawings. We find that by forming the horizontal mortar bed scores or the scores corresponding to the horizontal mortar beds in the wall transversely of the grain of the board, they may be formed very economically by the use of small circular milling saws 40 mounted on an ordinary milling machine. The scores running transversely of the grain are spaced apart a distance corresponding to the length of brick, or tile and are intermittent and staggered to represent the inter-binding joints of the brick in overlying courses in the wall. We may thus effect this scoring in a very satisfactory manner by 45 special forming tools which depress portions of the wood thus forming intermittent grooves which extend in the common direction of the grain of the wood and a clean cut score is effected without causing a tearing or splintering of the groove edges.

It will be readily understood that the grooves 15 may be formed, as illustrated in Figs. 1 to 3 inclusive, by positioning the board 15 in a holder or frame 20, the frame 20 may be provided with any convenient 70 means for securing the slab 16 thereto, and as shown in Fig. 1, a bar 21 is provided which may be maintained in clamped engagement with an edge of the board by screw members 22. This frame is of such 75 shape and size as to be conveniently mounted upon a bed 24 of a milling machine or similar machine suitable for the purpose of rotating small circular saws 25. As shown in the drawings, the saws 25 may be mounted 80 upon an arbor or bar 26 which has spacing rings 27 therebetween of such length as to space the saws a distance apart corresponding to the distance between the grooves or scores 15. The arbor 26 may therefore be 85 suspended upon the centering points 30 and 31 of the machine and a dog member 32 may connect the arbor 26 to the disc 34 of the machine spindle 35 whereby the saws 90 may be rotated at a proper speed to mill the slots 15 in the board when the latter is moved therebeneath by the machine bed 24 and frame 20. Any suitable means for properly maintaining the saws 25 in rigid relation to the supporting arbor 26 may be 95 provided, a preferred means comprising a key 36. In forming the transverse or intermittent slots 17, we prefer to use a tool in combination with the supporting frame 20 and arbor 26 which may comprise disc 100 members 38 mounted upon the arbor 26 with spacing rings 39 positioned therebetween which are of a width corresponding to one-half the length of the miniature brick spacing as shown in Fig. 13. The discs 38 have 105 the peripheries thereof notched to provide projecting lugs 40 and the key-ways in these disc members are so formed that the discs may be positioned upon the mandrel 26, with alternate discs having the lugs thereof in 110 alignment. When using this tool, it may be mounted in a milling machine as hereinbefore described. The spindle 35, however, will not be rotated at a saw cutting speed but may, if desired, be manually revolved. To 115 bring the mandrel 26 in proper relation to the frame 20, the latter is provided with a rack 42 secured along one side thereof which may engage a gear 43 rigidly mounted upon the mandrel 26 as shown in Fig. 5. The frame in this instance, however, is shifted so that the longitudinal grooves 15 which have been previously formed by the milling operation now extend parallel with the mandrel, so that when the lugs 40 of the discs 120 38 are brought into a compressive relation with the top surface of the board 16 carried by the frame member, the gear 43 may mesh with the teeth of the rack 42 in such manner 125 that the lugs 40 on alternate discs will form 130

5 scores or grooves as shown in Fig. 5 by depressing portions of the wood panels. The lugs 40 thus make a very clean cut groove, due to the fact that the discs 38 move in the same direction as the grain of the wood. It is to be understood, however, that if desired, the use of the discs 38 may be omitted and the board milled or grooved as shown in Fig. 6.

10 After the board is grooved in the manner shown in Figs. 1 and 5, it may then be coated with the selected pigments such as have been hereinbefore described. In Figs. 7, a section of the board is shown as being 15 coated with a plastic material 50 to represent a rough brick surface. The board when thus coated, is permitted to stand for a day or two until the surfacing 50 has sufficiently set to be cut or scored. The board may then 20 be placed again in the frame 20 and the longitudinal slots milled in the coating as shown in Fig. 8, the board, of course, being adjusted relative to the cutters on the mandrel 26 whereby the cutters will be in alignment with the previously formed grooves in the underlying supporting medium or board. If desired, plain disc members 51, as shown 25 in Fig. 9, may be mounted upon the mandrel 26 and may then roll or shear thin ribbons 30 of the coating material 50, causing these ribbons to be positioned at the bottom of the previously formed grooves 15 thus forming pigment grooves, 15^a, in the coating which are coincident with the mill grooves in the 35 board. The frame and board may then be shifted in the machine and the disc members 38 may then again be mounted upon the mandrel 26 whereupon proper registration of the lugs 40 with the intermittently 40 formed slots extending with the grain of the board conditions the apparatus for the formation of slots in the coating 50 which correspond to the vertical mortar joints between the brick.

45 As shown in Fig. 10 the lugs 40 of the disc 38 will depress short ribbons of the coating into the previously formed short slots in the board. This operation is effected by manually turning the spindle 35 in the manner hereinbefore described.

50 In Fig. 12 we show an alternate form of apparatus for effecting the formation of the short slots in the coating, the continuous slots having previously been formed by a milling operation in the manner shown in Figs. 8 or 9. In the use of this device, a frame 60 comprises a support for the coated board 16 while a manually manipulated notched bar 61 may have lugs 62 thereon of 55 a width corresponding to the height of a brick in the miniature. The ends of the bar 61 may engage in slots 63 formed in side portions of the supporting frame 60 to properly gauge the spacing of the bar. 60 Pressure exerted upon the top of the bar

will thus cause the lugs 62 to depress portions of the coating in alternate rows and upon the manual advancing of the bar 62 from one set of slots 63 to another, the bar may be shifted longitudinally, upon the formation of each succeeding row of slots, a distance corresponding to the width between the longitudinal slots. 70

If desired, all milling and rolling operations may be eliminated in effecting the 75 grooving of the coating 50 after it has been applied to the slotted surface of the board. In the latter case, however, the board may be milled both longitudinally and transversely as shown in Fig. 6 to form rectangles 80 which have a length corresponding to half the length of a brick. It will thus be seen that when forming the grooves in the coating by the use, say, of an apparatus such as shown in Fig. 12, the longitudinal or continuous slots may be formed by a bar having an unnotched edge by simply compressing the coating into the slots formed in the boards. In forming the short slots in the coating, however, the notched bar will be 85 so positioned as to not form slots corresponding to the slot portions 64. We find that such an apparatus is serviceable for all brick reproductions excepting glazed brick since the proper effect of a glazed coating 90 would be defective, due to the fact that the coating when applied flows into the slots formed in the board and would show indications of the slot portions 64, even though the coating had not been scored immediately 95 over these slot portions. This may be readily understood by referring to Fig. 13 wherein the grooves 15, which correspond to the horizontal mortar beds of the brick 100 wall, are shown as being formed transversely of the grain of the board or slab 16, while the grooves 17 extend longitudinally of the grain and are intermittent or alternately 105 staggered to represent the vertical mortar joints between the bricks in their respective 110 courses.

Having thus described our invention, we claim:

1. A method of imitating the outer appearance of a building wall in miniature 115 which comprises forming a plastic mass from material having a general texture corresponding to the texture of the material being imitated, scoring the surface of a plastic supporting medium by forming grooves 120 or slots in the surface thereof which correspond to the horizontal mortar beds and vertical mortar joints of the wall to be imitated, applying said material while in plastic form to the slotted surface of said supporting medium, drying the plastic material when so applied and removing those portions of the plastic material which lie immediately over the scores or slots formed in the supporting medium to form configura- 125 130

- 4
- tions therein corresponding to the miniature shape of the exposed surface of a brick or tile when in a wall.
2. A method of imitating the outer appearance of a brick wall which comprises forming slots in a surface of a board, the slots being so proportioned and spaced relative to each other so as to represent the mortar joints between the brick in the wall, applying pigment coatings to the scored surface of the board which in texture correspond to the texture of the bricks to be represented and removing those portions of the coatings which lie immediately over the scores in the board.
5. The process of imitating the outer appearance of a building wall in miniature which comprises scoring the surface of a plastic supporting medium by forming grooves therein horizontally and transversely of the medium, the spacing of the grooves being such as to correspond to the horizontal mortar beds and vertical mortar joints of the wall to be imitated, preparing a plastic medium by including the use of a pigment which, when mixed in the plastic material will impart a color thereto, corresponding to the color of the tile or brick in the wall to be imitated, applying said plastic material to the scored surface of said plastic supporting medium by spreading it over the grooves and intermediate surfaces thereof, treating said plastic material when so applied to give it a texture corresponding to the texture of the tile or brick in the wall being imitated and removing those portions of the plastic material which lie over the grooves formed in the supporting medium.
10. 3. A process of imitating the outer appearance of a brick building wall in miniature which comprises forming a plastic mass from material having a general texture corresponding to the texture of the brick to be imitated, applying said material while in plastic form to a solid supporting medium and scoring the plastic material to form configurations therein corresponding to the miniature shape of the exposed surface of the brick.
15. 4. A method of imitating the outer appearance of a building wall in miniature which comprises forming a plastic mass from material having a general texture corresponding to the texture of the material being imitated, scoring the surface of a plastic supporting medium, by forming grooves or slots in the surface thereof which correspond to the horizontal mortar beds and vertical mortar joints of the wall to be imitated, applying said material while in plastic form to the slotted surface of said supporting medium, drying the plastic material when so applied and removing those portions of the plastic material which lie immediately over the scores or slots formed in the supporting medium to form configurations therein corresponding to the miniature shape of the exposed surface of a brick or tile when in a wall and filling said slot with a material of a texture and color corresponding to the texture and color of the mortar beds in the brick wall to be imitated.
20. 5. A method of imitating the outer appearance of a brick wall which comprises forming slots in a surface of a plastic supporting board, the slots being proportioned and spaced relative to each other so as to represent the mortar joints between the brick in the wall, applying coatings to the scored surface of the board, which in texture corresponds to the texture of the bricks to be represented and removing those portions of the coatings which lie immediately over the scores in the board.
25. 6. The process of imitating the outer appearance of a building wall in miniature which comprises forming a plastic mass of a material having a general texture corresponding to the texture of the brick or tile to be imitated, applying said material while in a plastic condition to a solid supporting medium and treating the surface of the plastic material with fine sand or a like material to give it a surface corresponding to the surface of the material in the wall being imitated.
30. 7. A process of imitating the outer appearance of a building wall in miniature which comprises forming a plastic mass of a material having a general texture corresponding to the texture of the brick or tile to be imitated, applying said material while in a plastic condition to a solid supporting medium and treating the surface of the plastic material with fine sand or a like material to give it a surface corresponding to the surface of the material in the wall being imitated.
35. 8. The process of imitating the outer appearance of a building wall in miniature which comprises milling equidistantly spaced apart grooves in the surface of the plastic supporting medium, forming intermittent transverse grooves therein, applying plastic material to the grooved surface of the supporting medium, drying the plastic material after being applied, removing those portions of the material which lie over the parallel continuous grooves by a milling operation and removing those portions of the plastic material which lie over the intermittent grooves by depressing those portions into the intermittent grooves formed in the plastic supporting medium.
40. 9. The method of imitating the outer appearance of a building wall in miniature which includes the steps of forming a plastic mass from material which will have a texture corresponding to the texture of the material being imitated in the wall, scoring a board by a milling operation to form continuous parallel extending grooves which extend transversely of the grain of the board, forming intermittent grooves trans-

- versely of the parallel grooves by making depressions therein which extend parallel with the grain of the board, applying the plastic material to the board when so scored, 5 removing those portions of the plastic material lying over the grooves by the same milling and depressing operations which effect the formation of the grooves in the board.
10. The process of imitating the outer appearance of a building wall in miniature which comprises scoring the surface of a plastic supporting medium by forming grooves therein horizontally and transversely of the medium, the spacing of the grooves being such as to correspond to the horizontal mortar beds and vertical mortar joints of the wall to be imitated, preparing a plastic medium by including the use of a pigment which, when mixed in the plastic material, will impart a color thereto, corresponding to the color of the tile or brick in the wall to be imitated, applying said plastic material to the scored 15 surface of said plastic supporting medium by spreading it over the grooves and intermediate surfaces thereof, treating said plastic material when so applied to give it a texture corresponding to the texture of the tile or brick in the wall being imitated, removing those portions of the plastic material which lie over the grooves formed in the supporting medium and filling the grooves with a material which will impart 20 the appearance of mortar thereto.
11. A process of imitating the outer appearance of a building wall in miniature which comprises forming a plastic mass of an oil and pigment having a general texture corresponding to the texture of the wall to be imitated, applying said material while in plastic condition to a solid supporting medium and treating the surface of the plastic material to give it a physical appearance corresponding to the physi- 25 cal appearance of the material in the wall being imitated.
12. The process of imitating the outer appearance of a building wall in miniature which comprises milling equidistantly spaced apart grooves in the surface of the plastic supporting medium, forming intermittent transverse grooves therein, applying plastic material to the grooved surface of the supporting medium, partially drying the plastic material after being applied, deforming those portions of the material which lie over the parallel continuous grooves to reproduce the grooves in the plastic material which lies over the continuous grooves and forming intermittent grooves in the plastic material by depressing those portions of it which lie over the intermittent grooves formed in the supporting medium. 30
13. The method of imitating the outer appearance of a building wall in miniature which includes the steps of forming a plastic mass from material which will have a texture corresponding to the texture of the material to be imitated in the wall, scoring a board by a milling operation to form continuous parallel extending grooves which extend transversely of the grain of the board, forming intermittent 35 grooves transversely of the parallel grooves, by forming depressions which extend parallel with the grain of the board, applying the plastic material of the board when so scored, removing those portions of the plastic material from the outer plain thereof by the same milling and depressing operation which effects the formation of the grooves in the board, and applying a material to the grooves which will be representative of the mortar joints in the wall. 40
- In testimony whereof, we hereunto affix our signatures.
